FIG. 2.

Fig. 3.

Fig. 1 is a front view of a tuxedo shirt embodying my new design;

Fig. 2 is a front view on a larger scale of the bosom portion of the tuxedo shirt shown in Fig. 1; and

Fig. 3 is a detail view on a still larger scale of the applique ornamentation of the bosom portion of the tuxedo shirt shown in Figs. 1 and 2.

The essential features of my new design for a tuxedo shirt reside in the applique ornamentation, as shown particularly in Figs. 2 and 3 respecting the portion of the shirt shown in full lines in Fig. 1. The back of the shirt is conventionally plain.

I claim:

The ornamental design for a tuxedo shirt, substantially as shown and described.
